DUMPING GRATE

George L. Bridge, Clayton, Mo.

Application September 8, 1934, Serial No. 743,176

2 Claims. (Cl. 126—177)

This invention relates to stove grates and particularly to that type which are generally termed duplex grates.

This application is a continuation in part of my application Serial No. 676,085, filed June 16, 1933.

The ordinary duplex grates of conventional construction comprise a plurality of grate bars which are adapted to be turned or oscillated so as to permit the load of the grate to fall downwardly between the grate bars into the ash pit.

An object of this invention is to provide a swinging frame which supports the bars with means which may be readily manipulated to permit the supporting frame with the grates to swing downwardly in order to dump the entire load on the grate bars and to permit the return of the frame to its normal position, in combination with novel mechanism for holding the frame in normal position and to release the frame for dumping.

Other objects will be apparent from the following detail description, taken in connection with the accompanying drawing, in which—

Fig. 1 is a horizontal section through the stove approximately on the plane of the grate bars.

Fig. 2 is a vertical section approximately on line 2—2, Fig. 1.

Fig. 3 is a section on line 3—3, Fig. 1.

Fig. 4 is a detail perspective view of the grate rest and release.

A horizontally disposed stationary frame 1 is arranged inside of a stove adjacent the lower end of the fire pot, and supported by some suitable means, not shown in the drawing. Grate bars 2 and 3 are supported in a swinging frame 4 by means of trunnions on each end of the grate bars, 5 designating the rear trunnions, 6 designating a short front trunnion on the grate bar 3, and 7 designating a long trunnion on the front of the grate bar 2. The trunnions 5 rest in bearings 8 on the rear end of the frame 4 and the trunnions 6 and 7 in bearings 9 on the front end of the frame 4, the bearings 9 being provided with a retaining plate 10. The end of the trunnion 5 of the grate bar 2 is also journalled in a hanger 11 at the rear end of the frame 1 and the trunnion 7 is journalled in a hanger 12, which is integral with the front wall 13 of the stove.

The end of the trunnion 7 also passes through a suitable opening in a cover plate 14 and its end is shaped to receive an operating lever or shaker, as is well understood in the art.

Toothed members 15 and 16 that mesh with each other are connected to the front trunnions 6 and 7 of the grate bars, as best shown in Fig. 2,

so as to transmit the oscillating movement of the actuated grate bar 2 to the grate bar 3.

It will thus be seen that the frame 4 together with the grate bars is mounted for oscillation with the trunnions of the grate bar 2 acting as pivots.

A grate bar and release, comprising an elongated bar 17, is supported by the front wall 13 and a rear wall 18 of the stove, and parallel to the frame 4 and adjacent its outer edge when the frame 4 is in normal position. The bar 17 has two notches 19 to accommodate lugs 20 on the outer edge of the frame 4.

The bar 17 is supported for horizontal sliding movement and is resiliently held in position by a spring 21. Its front end is provided with a knob 22 for manual engagement. The arrangement is such that the bar 17 may be moved forwardly by means of the knob 22 when it is desired to dump the grate. By pulling the knob 22 forwardly the lugs 20 register with the notches 19, thus releasing the frame 4 and permitting it to swing downwardly while it is pivotally supported on the frame 1 by the trunnions 5 and 7 of the grate bar 2.

A bevelled ear 23 is positioned adjacent one of the notches 19 and the arrangement is such that as the frame 4 is swung upwardly the adjacent lug 20 engages the ear 23 pressing the bar 17 forwardly against the action of the spring 21 and thus bringing the notches 19 into registry with the lugs 20. As soon as the frame 4 has been moved upwardly far enough for the lugs 20 to clear the notches 19, the spring 21 causes the bar 17 to return to its normal position, the frame 4 is manually released and comes to rest with the lugs 20 engaging the top of the bar 17, thus supporting the frame 4.

For convenience and appearance a hinged door 24 covers the end of the trunnion 7 and the front end of the bar 17.

The frame 4 may be returned to normal position by means of a shaker member attached to the end of the trunnion 7. This function results by reason of a lug 25 on the rear end of the frame 4, and a lug 26 on the plate 10, which lugs are in the path of the grate bars when they are rotated. That is to say, after a partial revolution in either direction, corners of the grate bars strike the lugs 25 and 26, prohibiting further movement of the bars relative to the frame and permitting the frame to be moved by the shaker member.

It will be obvious, from the foregoing description, that the invention accomplishes its pur-

poses, that of providing simple and convenient means for permitting the dumping of a grate. Various changes may be made in the details of construction, within the scope of the appended claims, without departing from the scope of this invention.

I claim:

1. A grate comprising a pivotally supported frame provided with means for supporting fuel, and having a lug projecting from the outer edge thereof, in combination with an elongated member slidably mounted on a stationary support, arranged parallel to and adjacent the outer edge of the frame when the frame is in normal position, so proportioned and positioned as to permit said lug to rest upon the upper side of said member and thereby support the frame, having a notch in its edge adjacent the frame to permit the lug to pass therethrough when the said member is shifted, and having a bevelled surface underneath and adjacent the notch whereby when the frame is shifted upwardly from dumping position the lug will engage the bevelled surface to shift the mem-

ber and permit the lug to pass through the notch.

2. A grate comprising a pivotally supported frame provided with means for supporting fuel, and having a lug projecting from the outer edge thereof, in combination with an elongated member slidably mounted on a stationary support, arranged parallel to and adjacent the outer edge of the frame when the frame is in normal position, so proportioned and positioned as to permit said lug to rest upon the upper side of said member and thereby support the frame, having a notch in its edge adjacent the frame to permit the lug to pass therethrough when the said member is shifted, having a bevelled surface underneath and adjacent the notch whereby when the frame is shifted upwardly the lug will engage the bevelled surface to shift the member and permit the lug to pass through the notch, and a spring associated with the member and positioned and adapted to move the member and to yieldingly hold the member in a position to support the frame.
